(57) **CLAIM**

The ornamental design for a reversible cooking rack, as shown and described.

DESCRIPTION

FIG. 1 is a perspective view of a reversible cooking rack, showing our new design;

FIG. 2 is a top view thereof;

FIG. 3 is a bottom view thereof;

FIG. 4 is a side view thereof;

FIG. 5 is another side view thereof;

FIG. 6 is a front view thereof; and,

FIG. 7 is a rear view thereof.

The broken lines in the drawings depict portions of the reversible cooking rack that form no part of the claimed design.
